(57) **CLAIM**

I claim the ornamental design for a pair of display brackets for boards, as shown and described.

DESCRIPTION

FIG. 1 is a perspective view of a pair of display brackets for boards, showing a single board in broken lines, of my new design;

FIG. 2 is a left-side elevational view of one of the display brackets of FIG. 1, it being understood that the other display bracket is a mirror image thereof and omitted for clarity of illustration;

FIG. 3 is a right-side elevational view of FIG. 2;

FIG. 4 is a front elevational view of FIG. 2;

FIG. 5 is a rear elevational view of FIG. 2;

FIG. 6 is a top plan view of FIG. 2;

FIG. 7 is a bottom plan view of FIG. 2;

FIG. 8 is a perspective view of a second embodiment of a pair of display brackets for boards, showing a double board in broken lines;

FIG. 9 is a left-side elevational view of one of the display brackets of FIG. 8, it being understood that the other display bracket is a mirror image thereof and omitted for clarity of illustration;

FIG. 10 is a right-side elevational view of FIG. 9;

FIG. 11 is a front elevational view of FIG. 9;

FIG. 12 is a rear elevational view of FIG. 9;

FIG. 13 is a top plan view of FIG. 9; and,

FIG. 14 is a bottom plan view of FIG. 9.

The broken lines showing a board in FIG. 1 and two boards in FIG. 8 depict environmental matter and form no part of the claimed design.
